HYDRAULIC EXPANSIVE REAMER

James J. Santiago, Los Angeles, Calif., assignor
to John Grant, Los Angeles, Calif.

Application September 5, 1933, Serial No. 688,112

7 Claims. (Cl. 255—76)

This invention has to do with hydraulically actuated expansive reamers and the like. As will be readily understood from a consideration of what follows, the invention is generally applicable 5 to hydraulically expanded tools of various characters and for various uses, as the invention has to do with the means of hydraulic expansion and not with the particular nature and purpose of the cutters or other elements which are expanded 10 and contracted. However, as the device in its present form has been designed particularly in connection with an expansive well reamer, and as its utility may be readily understood when described in that connection, the following description 15 will deal with the invention as applied to such a well reamer, but without any implied limitations thereto.

In certain types of well reamers designed to be expanded by hydraulic pressure it is necessary 20 to shut off free circulation of the circulation fluid in order that the full or nearly full hydraulic pressure may be applied to the piston or other element to insure expansion of the cutters. The hydraulic element is supplied with fluid pressure via the 25 circulating fluid which, when the tool is in operation, provides the circulation that carries the cuttings up out of the hole. Thus, when the tool is expanded and in operation the circulation system must be open so that the fluid may flow. If 30 that circulation system be also kept open during the time pressure is applied for expanding the cutters, it often occurs that the pressure is not sufficient to cause cutter expansion; and there is no positive indication at the surface that the 35 cutters have not expanded.

On the other hand, if arrangements be made to close off the circulation when the cutters are contracted, in order to have full pressure for expansive action, then there is no outlet for draining the drill pipe of its contained fluid as the 40 drill pipe is lifted from the well; resulting that as each length or stand of pipe is uncoupled the fluid in it escapes over the derrick and the operators.

Difficulties have also been encountered in such 45 types of reamers due to excessive wear of the high velocity muddy fluid on any constricted or pressure restrictive openings which may be used, necessitating replacement or re-building if the tool is to be kept in proper operation.

It is included in the objects of my invention to 50 provide a hydraulic pressure actuated mechanism which will overcome the difficulties above described and to provide for certainty of cutter expansion, for minimizing wear and affording easy

replacement in case of wear, and provide at the same time for adequate drainage of the drill pipe when it is lifted from the hole.

A typical form of my invention, typically applied to an illustrative expansive reamer, is illustrated in the accompanying drawing, in which

Fig. 1 is a central vertical section showing the tool in its contracted position and

Fig. 2 is a similar view showing the tool in its expanded position.

In the drawing I illustrate an expansive reamer of the same general type as is described in application Ser. No. 665,377 filed April 10, 1933 for Reamer or well scraper.

This type of reamer has in its body 10 a transverse cutter slot 11 accommodating a pair of vertically swinging cutters 12 pivoted on a horizontal pin 13 and actuated between the positions shown in the figures by links 14 which connect at their upper ends to a piston or plunger acted upon by the hydraulic pressure.

In the type of reamer described in said application a pair of circulation passages 16 (only one of which is shown in the drawing here) leads down from the cylinder bore 15 and delivers into a bore or cavity 17 directly above the pin 18 of bit 19 which is secured to the lower end of the body, the bit having circulation passage 20 through it. Also, leading upwardly and outwardly from the cavity 17 is a pair of passages 21 which direct circulation upwardly and outwardly under cutters 12 when expanded. An exterior sleeve 25 serves to strengthen the body and also serves to cover the circulation passages 16 which are preferably formed as grooves in the exterior surface of the body, but these features need not here be entered into. It is sufficient for the purposes of the present application to note that in such a tool there is a cutter or cutters, or similar elements, movable for expansion and contraction, and that there is a circulation passage which, as soon as it is open to the fluid in the drill pipe, discharges circulating fluid at a point or points exterior of the tool, and that such circulation passage should be open when the tool is expanded in order to provide the liquid circulation necessary for carrying away the cuttings.

Cylinder bore 15 is open at its upper end to communicate with the fluid passage 41 through the drill pipe to which the tool is attached.

In accordance with my present invention a preferably double-headed plunger operates in the cylinder bore, this plunger having an upper head 30, an intermediate rod 31, and a lower head 32. Upper head 30 is perforated with passages 30a,

and may be considered primarily as a valve member, although it may also perform as a pressure head, as will be pointed out. Lower head 32 operates in a liner 33 which forms the lower reduced part of the cylinder bore; this head carries packing 34 and fits the liner bore closely. The liner rests at its lower end on body shoulder 33a, and a compression spring 35 rests on the upper end of the liner and pushes upwardly on upper head 30 to move the plunger upwardly and normally to hold it in its upper position, (Fig. 1). In this position of the plunger cutters 12 are collapsed; when the plunger moves down the cutters are expanded.

In the normal position of Fig. 1 lower plunger head 32 covers the port 16a where passage 16 communicates with the cylinder bore. The long skirt 30b of upper head 30 lies above the relief port 40 such a distance that preferably that port is not covered by head 30 until about the time port 16a is opened by head 32. The drawing shows such relative positions of the ports that port 40 begins to close as port 16a begins to open; it is preferable that the two ports be not fully open together.

When fluid pressure from the drill pipe is applied to the plunger in the position of Fig. 1, that pressure, acting on the lower head 32 causes the plunger to move down, and to expand the cutters, under the full fluid pressure relieved only by the small port 40. The action of expansion is therefore positive, and under almost full pressure, until circulation port 16a is opened. Port 16a (passage 16) is of a size to allow relatively free circulation from the cylinder bore, but is smaller than the passage through the drill pipe (indicated at 41), so that sufficient back pressure is set up in the cylinder still to force the plunger down. And, additionally, there is some pressure exerted downwardly on upper head 30, although the passages 30a have a larger area than passage 16 and the back pressure above head 30 is therefore smaller than that on lower head 32. The back pressure on head 30 may be increased by making openings 30a smaller; they may be made in total area as small as that of passage 16; but I prefer to keep them relatively large to minimize wear and to keep higher the back pressure on the lower head.

In any case, the pressure on the lower head after port 16a opens, is sufficient to cause complete cutter expansion. Port 16a does not open until the cutters are well toward the fully expanded position of Fig. 2; the dotted lines show cutter positions with the port about half uncovered. At this time relief port 40 is closed or closing; and, the cutters being then far enough out to take a biting engagement with the wall of the hole, the fluid pressure on the plunger and the upward thrust of the formation on the cutters as the tool is lowered, cause the completion of positive expansion. Port 16a may be lowered if desired to a point where the cutters are substantially completely expanded when the port is uncovered, but I prefer to have it uncovered and fluid circulation to the cutters begin, at about the time the cutters reach the position shown and begin cutting more or less fully.

On relief of pressure the spring immediately moves the plunger up and collapses the cutters. Relief port 40 is then open and allows drainage of fluid from the drill pipe as it is raised from the hole. A relatively small port at 40 suffices for drainage—a port much smaller than pipe passage 41 or circulation passage 16; so that port 40,

to care for drainage, does not have to be large enough to relieve any considerable fraction of the pressure in the cylinder. And the size of port 40 may be changed to suit differing situations; it may be enlarged if work is being done in soft strata where expansion is easy; it may be reduced where expansion is difficult. Provision of port 40 in the removable bushing 40a facilitates such change by substitution; and the bushings may be of hardened steel to minimize wear of the orifice. And whenever that port becomes worn by the fluid flow, the bushing may be replaced by a new one. In cases where expansion is exceptionally difficult a solid plug may be substituted for the bushing so that full unrelieved pressure is then exerted on the plunger. And the suggested lower placement of port 16a provides for a longer application of that full pressure. I prefer, however, to use a bushing with at least a small port 40 wherever possible, to provide for drainage.

I claim:

1. In an hydraulic expansive tool, a body with a cylinder therein, an expansively movable cutter on the body, a plunger movable in the cylinder, connected to the cutter to move it and exposed to fluid pressure from the drill pipe to which the body is connected, a circulation port leading from the cylinder and discharging from the body, and a relief port leading from the cylinder, said circulation port arranged to be opened by movement of the plunger in cutter expanding direction, and said relief port being closed by the same movement of the plunger.

2. In an hydraulic expansive tool, a body with a cylinder therein, an expansively movable cutter on the body, a plunger movable in the cylinder, connected to the cutter to move it and exposed to fluid pressure from the drill pipe to which the body is connected, a circulation port leading from the cylinder and discharging from the body, and a relief port leading from the cylinder, said circulation port arranged to be opened by movement of the plunger in cutter expanding direction, and said relief port being closed by the same movement of the plunger not later than the opening of the circulation port.

3. In an hydraulic expansive tool, a body with a cylinder therein, an expansively movable cutter on the body, a plunger movable in the cylinder, connected to the cutter to move it and exposed to fluid pressure from the drill pipe to which the body is connected, a circulation port leading from the cylinder and discharging from the body, and a relief port leading from the cylinder, said circulation port arranged to be opened by movement of the plunger in cutter expanding direction, and said relief port being closed by the same movement of the plunger, and said relief port being formed in a removable and substitutable bushing whereby the size of the relief port may be adjusted.

4. In an hydraulic expansive tool, a body with a cylinder therein, an expansively movable cutter on the body, a plunger movable in the cylinder, connected to the cutter to move it and exposed to fluid pressure from the drill pipe to which the body is connected, a circulation port leading from the cylinder and discharging from the body, and a relief port leading from the cylinder, said circulation port arranged to be opened by movement of the plunger in cutter expanding direction, said relief port being closed by the same movement of the plunger not later than the opening of the circulation port, and said relief port being formed

in a removable and substitutable bushing whereby the size of the relief port may be adjusted.

5. In an hydraulic expansive tool, a body with a cylinder therein whose upper end is in communication with the drill pipe to which the body is attached, an expansively movable cutter on the body, a plunger movable in the cylinder and connected to the cutter to move it, the plunger having a lower head fitting the cylinder and an upper passaged head also fitting the cylinder, a circulation passage leading from the cylinder at a point to be uncovered by the lower head on downward movement of the plunger, and a relief port leading from the cylinder at a point to be covered by the upper head on downward movement of the plunger.

6. In an hydraulic expansive tool, a body with a cylinder therein whose upper end is in communication with the drill pipe to which the body is attached, an expansively movable cutter on the body, a plunger movable in the cylinder and connected to the cutter to move it, the plunger having a lower head fitting the cylinder and an upper passaged head also fitting the cylinder, a circulation

passage leading from the cylinder at a point to be uncovered by the lower head on downward movement of the plunger, and a relief port leading from the cylinder at a point to be covered by the upper head on downward movement of the plunger at a time not later than the uncovering of the circulation passage.

7. In an hydraulic expansive tool, a body with a cylinder therein whose upper end is in communication with the drill pipe to which the body is attached, an expansively movable cutter on the body, a plunger movable in the cylinder and connected to the cutter to move it, the plunger having a lower head fitting the cylinder and an upper passaged head also fitting the cylinder, a circulation passage leading from the cylinder at a point to be uncovered by the lower head on downward movement of the plunger, and a relief port leading from the cylinder at a point to be covered by the upper head on downward movement of the plunger, said relief port being formed in a bushing whereby its effective size may be adjusted.
